UNITED STATES PATENT OFFICE.

HAROLD CAMINEZ, OF DAYTON, OHIO.

ENGINE-PRESSURE-RECORDING INSTRUMENT.

Application filed May 17, 1923. Serial No. 639,579.

This invention relates to an engine pressure recording instrument, the same being adapted for use in connection with the cylinder and piston of any engine for the purpose of making a record of engine pressure.

The object of the invention is to provide an instrument which will directly produce a diagram of the pressure changes that occur in the cylinder of an engine during a cycle of operations extending over a period of time. The improved instrument will operate under the present day high engine speeds because in its design the inertia and friction effects on pressure indications have been almost entirely eliminated. The instrument is a rugged mechanical device and therefore possesses a decided advantage over the delicate optical instruments heretofore employed for the same duty.

The invention consists in the features of construction, combination and arrangement herein fully described, illustrated and claimed.

In the accompanying drawings:

Figure 1 is a vertical diametrical section through the instrument.

Figure 2 is an end elevation of the same.

Figure 3 is a bottom plan view thereof.

Figure 4 is a horizontal section through the instrument on the line BB of Figure 1 looking downwardly.

Figure 5 is a transverse section on the line AA of Figure 1 looking downwardly and showing the tongue guide in concentric position.

Figure 6 is a view taken on the same line but showing the tongue guide in eccentric position.

Figure 7 is a plan view of the collar which yokes the gears together.

Figure 8 shows the appearance of a record card after a record has been drawn thereon by the instrument.

In the improved recording instrument, the record card is carried on a drum which rotates about a central barrel as will hereinafter appear. This drum it is preferred to drive at engine camshaft speed, altho this is not essential. The instrument has an

automatic feed mechanism which shifts the card drum carrier along its longitudinal axis a small distance in every revolution of the drum. The appearance of the card produced by the instrument is graphically shown in Figure 8.

Referring now to the drawings, the frame

of the instrument designated at 1^a comprises an external threaded plug like extension 1 which is adapted to be screwed into the engine cylinder (not shown), for example in one of the spark plug holes. Mounted within the plug 1 is a reciprocatory piston 2 which is acted upon by the gas pressure in the engine cylinder. The piston 2 is held down by a coil expansion spring 3 bearing upon the flange of the piston 2, the travel of the piston 2 being limited by a stop nut 4 threaded into a barrel 12 which is an integral part of the frame 1^a. The position of the nut 4 is adjustable and the adjustment may be maintained by a jam nut 5. The motion of the piston 2 is transmitted to a pencil or stylus 8 by means of a short two-armed lever 6, pivoted as shown and engaged in a slot in the flange of the piston 2, and in a similar recess in the bell crank lever 7 as clearly shown in the Figure 1, the proportions of the levers 6 and 7 being such as to magnify the motion of the piston sufficient to allow the pencil 8 to bear against a record card which is held by suitable clips 8^a on the drum 9.

The height of the drum 9 is determined by the position of a drum carrier 10. Drum carrier 10 is threaded upon and surrounds the barrel 12 so that the height of the drum carrier is varied by rotating the same. The position of the drum carrier 10 also determines the position of a spring compressor 11. A differential screw adjustment is employed whereby the travel of the spring compressor 11 is proportional to, but less than that of the drum carrier 10. This action is obtained by providing the spring compressor 11 with one or more projections 11^a having a sliding fit in grooves or guide-ways 11^b in the barrel 12, so that the spring compressor can not rotate with respect to said barrel. The upper end of the spring compressor spindle is slotted as shown in Fig. 1 within which the tongue guide 39, described later, operates. The slotted end of the spindle 11 extends into the hollow shaft 27 when in the position shown in Fig. 1.

The spring compressor spindle is threaded into the head 10^a of the drum carrier. This thread is of a finer pitch than the thread on the barrel 12 on which the drum carrier 10 moves. With the above arrangement, if the spring compressor spindle 11 is provided with sixteen threads per inch while the bar-

reel 12 is provided with twelve threads per inch, then when the drum carrier 10 is rotated twelve turns it moves on the barrel one inch, while the spring compressor spindle 11 is drawn up into the drum carrier head 10^a a distance of twelve divided by sixteen or three-fourths of an inch. The movement of the spring compressor 11 with respect to the barrel 12 for a vertical travel of one inch of 10 the drum carrier 10 is therefore one minus three-fourths of an inch which is equal to one-fourth of an inch.

The drum 9 is formed with a gear face 13 which meshes with a gear 14 on and driven 15 by a tubular shaft 15. The gear 14 is held in mesh with the gear face 13 by means of a collar 16 having the general form of the numeral 8 as shown in Figure 7. Within the bore of the shaft 15 is another shaft 17 which 20 may be driven at camshaft speed either through suitable connection at 18 with one end of the shaft 17 or by means of helical gears 19 and 20. A combined friction and positive clutch 21 is provided at the top of 25 the shaft 17 for the purpose of connecting the shaft 17 with the shaft 15, the latter in turn driving the drum 9. When the clutch spindle 21 is moved upwardly, it is out of clutching engagement with the shaft 15 but 30 rotates with the gear 20. One or more springs or clutch members 22 are secured to the clutch spindle. By pushing the clutch spindle downwardly for a portion of its travel, frictional connection is first made be- 35 tween the clutch and the shaft 15 by means of the springs 22 and 22^a pressing against an internal annular ridge of the shaft 15. This frictional engagement is desirable in order that the shaft be smoothly engaged. Fur- 40 ther downward movement of the clutch spindle 21 eliminates the frictional connec- 45 tion as the springs 22 and 22^a move into an annular recess 26 in the shaft 15. At the same time, a projection 24 on the clutch spindle comes into contact with a pin or pro- 50 jection 25 on the upper end of the shaft 15 so that positive connection is made between the clutch spindle 20 and the shaft 15 at a fixed angular relation between these two members. This is necessary in order that the angular position of the drum 9 with respect to the shaft 17 can be predetermined and kept constant.

27 designates a tubular shaft having there- 55 on a hand wheel 28 which is attached to the shaft 27 by means of a pin or key 29 which extends into a groove 30 in the shaft 27. This enables the shaft 27 to be turned or ro- 60 tated by the hand wheel 28 and at the same time allows the hand wheel to move longitudinally of the shaft 27 for a purpose which will presently appear. The plate 40 is sup- 65 ported in fixed position by means of a yoke or anchoring member 41 secured to the en-

slidable relation to the guide members 42 of the frame 1. The drum carrier 10 may therefore be raised and lowered by turning hand wheel 28.

An automatic feed mechanism is provided 70 to turn the drum carrier a fraction of a revolution at every revolution of the drum 9. To this end the drum 9 has attached to the top thereof a ring 31 adjustable around the axis of the drum by means of set screws 75 31^a and slots 31^b which provide for advancing or retarding the driving movement of the ring 31 as will appear. The ring 31 has a projection 32 which engages for a portion 80 of a revolution with one or more tongues 33 which extend through guideways in the head of the drum carrier 10. In Figure 5 the automatic feed is disengaged while in Figure 6 the automatic feed is engaged. The feed mechanism is thrown into and out of 85 operation in the following way. When the hand wheel 28 is pushed downwardly with respect to the shaft 27, it pushes downwardly the shaft 36 which latter passes through the shaft 27. A pin 37 in the slotted end of 90 the shaft 36 cooperates with an inclined slot 38 in a tongue guide 39; pushing the hand wheel downwardly causes the guide 39 to be thrust laterally from the concentric position shown in Figure 5 to the eccentric position 95 shown in Figure 6. The tongues 33 are pro- 100 vided with upstanding pins or projections 35 which fit into an annular groove 35^a in the guide 39. When the guide is in an eccentric position as shown in Figure 6, it causes one 105 or more of the tongues 33 to project through the slots in the drum carrier so that at every revolution of the drum 9, the projection or lug 32 on the ring 31 will engage for a frac- 110 tion of a revolution with one of the tongues 105 33 and thereby cause the drum carrier 10 to perform a partial revolution. The length of the path traveled by the projection 32 carrying with it the tongue 33 will depend upon the degree of eccentricity of the guide 115 39.

The direction of the threads on the barrel 12 is such that the automatic feed mech- 120 anism will cause the drum carrier 10 to de- 125 scend when the feeding mechanism is in operation. In descending, the drum carrier 10 which has a coarser pitch on its threaded end than the spring compressor spindle 11, moves downwardly more rapidly than the spindle 11 and as a result the latter moves upward relative to the carrier 10.

However the spindle 11 is slowly moving downwardly all the time, proportional to but less than the movement of the drum car- 125 rier 10. As a result the upper end of the spindle 11 would eventually come in contact with the hand wheel 28 and would carry the handwheel upwardly with respect to the shaft 27. This action causes the pin 37 to move the guide 39 back to the concentric 130

position shown in Figure 5 and the automatic feed mechanism is thereby disengaged when the drum carrier has moved the limit of its travel. To acquire such a chart or record as shown in Fig. 8 is the ultimate aim of the invention, and it follows that for each explosion of the cylinder, the piston 2 of the device will move upwardly against the nut 4 causing the pencil 8 to press against the record card as is hereafter mentioned.

Since the drum 9 is rotating, say at cam-shaft speed, a line will be made on the record card, the length of which will denote the length of time that the pressure in the cylinder is greater than the pressure of the spring 3.

At the beginning of the test the lower end of the drum 9, together with the drum carrier 10 is at a position about midway on the threaded portion of the indicator barrel 12. At the same time the lower end of the spring compressor 11 will be in such a position, relative to the indicator barrel 12, so that very little pressure will be exerted on the spring 3. In other words, the spring 3 will be extended in length enough to reduce the pressure bearing on the flange of the piston 2. As the drum 12 rotates, (the automatic feed mechanism being in an eccentric position as shown in Fig. 6) an explosion occurs in the cylinder of the engine and a mark or line is made on the record card, which will show the length of time that the cylinder pressure exceeds the spring pressure.

For each succeeding explosion the tension on the spring 3 is increasing and as a result the mark will become smaller and smaller until a point is reached in which the mark will be practically just a dot. During this time the spindle or spring compressor 11 is slowly moving downwardly proportional to but less than the movement of the drum carrier 10. As a result the upper end of the spindle 11, eventually comes in contact with the handwheel 28 and carries the handwheel upward with respect to the shaft 27. As a result a series of marks made at regular intervals on the record card until the drum 9 and drum carrier 10 have reached the limit of their travel, will create a chart or record very similar to the one shown in Fig. 8, showing the work done by the cylinder during the elapsed time.

To clearly understand the operation of the working parts in this device it must be borne in mind that the member 12 is fixedly mounted against both rotation and longitudinal movement by means of the gland 1 in the spark plug opening of the engine in connection with which the device is to be used. It must be further carefully borne in mind that the member 11 is also non-rotatably mounted since it has a sliding fit by means of lugs 11^a in slots 11^b of the member 12.

The drive mechanism tending to rotate the rotatable parts of my device, either the gear 14 communicating with the gear 13 or the handwheel 28, serves to rotate first the member 9. No other portion of the recording means is rotated except when the handwheel 28 is pushed downwardly, the movement of the pin 37 forcing the slides 33 with their carrier into a position eccentric of the longitudinal axis of the member 11. When in this eccentric position as is fully disclosed in Figures 5 and 6, the slides 33 are in position to be engaged through a partial revolution by the lug 32 on the rotating member 9. The engagement of the member 32 with the member 33 will result in a partial rotation of the member 10^a. The member 10 having screw threaded engagement with the member 12 will, by its rotatable movement, be moved longitudinally thereof. Similarly its screw threaded portion 10^a due to its rotatable movement will be moved longitudinally of the member 11, but to a lesser degree since the pitch of the threads engaging with the member 11 is less than the pitch of the thread engaging with the member 12. This will cause a relative longitudinal and differential movement between the members 12 and 11. It should be understood that the member 39 does not rotate but merely extends into the slot of the upper portion of the member 11, the members 33 having lugs 35 adapted to be rotated around the circular guideway 35^a clearly shown therein in Figures 5 and 6.

I claim:

1. An engine pressure recording instrument embodying in combination, a rotary record card carrying drum, means for moving said drum in the direction of its longitudinal axis, a piston operated by engine pressure, a stylus operated by said piston, a yieldable resistance for said piston, a movable tensioning member for varying the force of said resistance, and differential gearing between said drum and tensioning member for the purpose described.

2. An engine pressure recording instrument embodying in combination, a rotary record card carrying drum, intermittently operating means for moving said drum in the direction of its longitudinal axis, a piston operated by engine pressure, a stylus operated by said piston, a yieldable resistance for said piston, a movable tensioning member for varying the force of said resistance, and differential gearing between said drum and tensioning member for the purpose described.

3. An engine pressure recording instrument embodying in combination, a piston operated by engine pressure, a stylus actuated by said piston, a rotary record card carrying drum driven by the engine, means for moving said drum axially, a yieldable

- resistance element for said piston, a movable tensioning member for said resistance element, and connecting means between said drum and tensioning member whereby the latter is moved in a predetermined ratio to the axial movement of the drum and means controlled by said drum for actuating said tensioning member.
4. An engine pressure recording instrument embodying in combination, a piston operated by engine pressure, a stylus actuated by said piston, a rotary record card carrying drum driven by the engine, means for moving said drum axially, a yieldable resistance element for said piston, a movable tensioning member for said resistance element, and means controlled by said drum for actuating said tensioning member.
5. An engine pressure recording instrument embodying in combination, a piston operated by engine pressure, a stylus actuated by said piston, a rotary record card carrying drum driven by the engine, means for moving said drum axially, a yieldable resistance element for said piston, a movable tensioning member for said resistance element, and connecting means between said drum and tensioning member whereby the latter is moved in a predetermined ratio to the axial movement of the drum.
6. An engine pressure recording instrument embodying in combination, a piston operated by engine pressure, a stylus actuated by said piston, a rotary record card carrying drum driven by the engine, a clutch for throwing the driving means into and out of gear, means for moving said drum axially, a yieldable resistance element for said piston, a movable tensioning member for said resistance element, and connecting means between said drum and tensioning member whereby the latter is moved in a predetermined ratio to the axial movement of the drum.

In testimony whereof I affix my signature.
HAROLD CAMINEZ.
